(57) **CLAIM**

We claim the ornamental design for a two-bottle container package, as shown and described.

DESCRIPTION

This design patent application is related to U.S. patent application Ser. No. 14/957,305 filed Dec. 2, 2015 entitled “Two Bottle Container”, which application is incorporated herein by reference.

FIG. 1 is a front perspective view of the two bottle container package in accordance with an embodiment of the present invention.

FIG. 2 is a rear perspective view thereof.

FIG. 3 is an alternate front perspective view thereof.

FIG. 4 is an alternate rear perspective view thereof.

FIG. 5 is a front view of a first part thereof, rear view is a mirror image.

FIG. 6 is a right side view of the first part of the two bottle container package, shown separately for completeness of illustration.

FIG. 7 is the left side view of the first part thereof.

FIG. 8 is a top view of the first part thereof.

FIG. 9 is a bottom view of the first part thereof.

FIG. 10 is an elevational section view of FIG. 8.

FIG. 11 is a perspective view of the second part of the two bottle container package, shown separately for completeness of illustration.

FIG. 12 is front view of a second part thereof, rear view is a mirror image.

FIG. 13 is a right side view of a second part thereof.

FIG. 14 is a left side view of a second part thereof.

FIG. 15 is a top view of a second part thereof.

FIG. 16 is a bottom view of a second part thereof; and,

FIG. 17 is an elevational section view of FIG. 15.

The broken lines shown in the drawings illustrate portions of the two bottle container package that form no part of the claimed design.
